UNITED STATES PATENT OFFICE.

JOHN E. W. FOGAL, OF QUINCY, ILLINOIS, ASSIGNOR TO QUINCY ELEVATOR GATE CO.,
OF QUINCY, ILLINOIS, A CORPORATION OF ILLINOIS.

ELEVATOR-GATE-OPERATING MECHANISM.

1,281,772.

Specification of Letters Patent. Patented Oct. 15, 1918.

Application filed December 26, 1917. Serial No. 208,826.

To all whom it may concern:

Be it known that I, JOHN E. W. FOGAL, a citizen of the United States, and a resident of Quincy, in the county of Adams and State 5 of Illinois, have invented a new and improved Elevator-Gate-Operating Mechanism, of which the following is a full, clear, and exact description.

This invention relates to a gate or door 10 operating mechanism of that type carried by the car or elevator whereby the door or gate at any floor can be opened or closed by the mechanism on the car when controlled by the attendant.

15 The invention has for its general objects to improve and simplify the construction and operation of mechanism of the character referred to as to be reliable and efficient in use, comparatively simple and inexpensive 20 to manufacture and install, and so designed that there is a minimum of trouble arising from parts getting out of order.

A more specific object of the invention is the provision of one or more lifting or pick- 25 up devices arranged on the car whereby the pressing of a button by the attendant causes an electric motor on the car to operate through a suitable winding device to first throw the pick-up device into engagement 30 with a shaft door or gate and then lift or move the door or gate to open position, the pick-up device being so arranged that it will be in operative relation to the gate or door even though a landing is made a few inches 35 above or below the floor, the closing or lowering of the gate or door being effected by the pressing of another push-button which reverses the motor so as to allow the winding means to unwind.

40 A further object of the invention is to provide a switch which will automatically open the circuit of the car-lifting motor when the car has been stopped and a shaft door or gate is opened.

45 With such objects in view, and others which will appear as the description proceeds, the invention comprises various novel features of construction and arrangement of parts which will be set forth with particularity in the following description and claims appended hereto.

In the accompanying drawings, which

illustrate one embodiment of the invention and wherein similar characters of reference indicate corresponding parts in all the 55 views,

Figure 1 is a vertical section of a freight elevator car and a portion of a shaft showing a gate closed, the car having the improved gate-operating means installed thereon, and showing the parts of the gate-opening means in normal position by full lines and raised position by dotted lines;

Fig. 2 is a front view of the elevator, showing the gate-lifting mechanism; 65

Fig. 3 is a diagrammatic view of the circuits and electrical devices for the gate-operating mechanism;

Figs. 4 and 5 are detail sectional views on the lines 4-4 and 5-5, respectively, Fig. 1; 70

Fig. 6 is a detail view showing the gate-lifting devices just prior to releasing the gate at the end of the closing movement; and

Fig. 7 is a detail sectional view of a modification of the gate-lifting device. 75

Fig. 8 is a diagrammatic view of the cut-out switch.

Referring to the drawings, A designates an ordinary elevator of any approved construction which includes a floor 1, a frame 2 having hollow-channel-shaped uprights 3 at the front corners to constitute guides for the movable parts of the gate-lifting devices, and the frame also includes a horizontal beam 4 on which is mounted a braced shelf 5 that carries a gate-operating motor 6, the drum shaft 7, worm gearing 8 and winding drums 9. At the front, upper corners of the car frame are pulleys 10 over which run 90 lifting cables 11 which wind on the drums 9 that are carried by the ends of the shaft 8 which extends entirely across the top of the car A.

The gate-operating cables 11 extend 95 downwardly through the vertical guides 3 and each is connected at its lower end with a gate-lifting device B. Each device comprises a vertically disposed bar or weight 12 made in two sections b, as shown in Fig. 5, 100 and between these sections and connected therewith are two pairs of parallel links 13 which are connected with a pick-up element 14 in the form of a vertically disposed bar

having teeth 15 in its outer edge. The weight 12 is provided with rollers 16 which engage the walls of the guide 3 to insure easy movement of the gate-lifting devices B. 5 On the bottom of the pick-up element 14 is a hook 17 that engages a fixed pin 18 whereby the pick-up device is prevented from moving upwardly with the slide or weight 12 during the initial upward movement of the latter, and consequently the normally inclined links 13 will throw the pick-up element 14 laterally into operative engagement with the gate C, which latter has a tooth or projection 19 for engagement by 15 any one of the teeth 15 of each lifting device. After the initial movement of the weights or slides 12 of the lifting devices the links will be in an approximately horizontal position, with the pick-up elements 14 fully projected, and the links and pick-up elements will remain in this position during 20 the entire lifting movement of the gate C, as will be clearly seen from the dotted lines in Fig. 1. When the lifting devices B are lowered the lower ends of the pick-up elements 14 will strike the pins 18 and thereby be arrested while the weights 12 continue their downward movement until they strike the floor 1, and during this downward movement of the weights 12 the elements 14 are retracted so as to clear the teeth 19 on the gate C. The car can now move up or down free of the gate. During the retracting movement of the toothed elements 14 the hook 17 35 automatically engages under the pin 18.

On the bottom of the floor is a switch D which is in the car-lifting motor circuit, and the switch includes a lever 20 which carries a contact 21 bridging the fixed contacts 40 22, and the lever projects out of the switch box 23 and is engaged by a spring-lifted pin 24 projecting through the floor 1 of the car at a point in line with the lower end of the weight 12, so that when the latter is in lowered 45 position the switch D is normally closed, and as soon as the weight 12 is lifted the switch D is automatically opened, so that it will be impossible to move the car after the gate-operating means has been 50 brought into play. Preferably two cut-out switches D are employed, one at each front corner of the floor.

At the upper and lower ends, respectively, of the guides 3 for the lifting devices B 55 are switches E and E' that are operated by the slides 12, so that the motor is automatically stopped when the gate is fully lifted or fully lowered. These switches will be described more in detail and the controlling 60 push-buttons in connection with the diagram shown in Fig. 3.

The gate or door C is movable in vertical guideways 25 at opposite sides of the doorway 26 in the wall of the elevator shaft 27, 65 the gate C being adapted to rest on the

landing or floor 28 when in closed position. If desired, the gate may have a serrated bar 19^a, as shown in Fig. 7, and the gate-lifting element 14^a may have a single projection 15^a to engage with the teeth of the bar 19^a 70 on the gate, which is the reverse of the arrangement shown in Fig. 1. In either case the gate can be engaged and raised to its full height even though the car be stopped a few inches above or below the landing. 75

Referring to Fig. 3 of the drawing, m designate the current supply mains which are arranged in the elevator shaft and connected with a juncture box 30, from which runs a flexible cable 31 to a juncture box 32 80 on the car A. From the juncture box leads a supply cable 33 that connects with the motor 6 and with the reversing switch-board 34 carried by the car for controlling the direction of rotation of the armature or worm shaft 35 of the motor. On the shaft is an electrically-operated brake 36 of any approved design. The switch-board 34 may be of any approved design so that it is unnecessary to consider the same in detail, its function being to provide the necessary circuit connections for driving the motor in either direction and for stopping the same. On the car are arranged pushbutton switches 37, 38 and 39 adapted to be operated by the attendant for respectively effecting the closing of the motor circuit to open the gate, the closing of the motor circuit to lower the gate, and the opening of the motor circuit in case it is desired to stop the gate at any point in its travel, to avoid accident, or for any other purpose. In other words, the attendant has full control of the operation of the gate at all times. The stopping of the gate at the end of its travel is effected by the switches E and E', as hereinbefore mentioned. These switches are connected with the switch-board 34 and through the same with the motor, each switch comprising a trip or bowed spring 105 member 40 arranged in the guideway 3, as shown in Fig. 1, and this trip operates on a movable contact 41 that engages a fixed contact 42. When the trip or member 40 is moved laterally by the weight 12 the lever 110 41 is moved to open-circuit position, as is indicated by the switch E', Fig. 3. When the weight moves out of engagement with the trip 40 the switch automatically closes. In Fig. 3 the gate is closed, which means 115 that the switch E is closed and the switch E' opened. To open the gate the attendant presses on the pushbutton switch 37 which controls the motor circuit in such a manner that the motor will operate to raise the gate, and as soon as the weight 12 passes out of co-operative relation with the lower switch E', this switch closes but will have no effect on the circuit for the present. As the weight 12 moves upwardly it engages the 120 125 130

trip 40 of the upper switch E and opens the same, which will cause the motor to stop. To lower the gate the attendant presses the pushbutton switch 38, which closes the circuit through the lower switch E' and effects the reversing of the motor, which allows the gate to close, and as the weight 12 moves downwardly, the upper cut-out switch E closes and finally the lower cut-out switch 10 E' opens. In Fig. 3 the power cut-out switches D that are carried by the floor of the elevator and are controlled by the gate-lifting devices B are connected with the juncture boxes 32 and 43, the latter, like 15 the former, being mounted on the car and being connected by a flexible cable 44 with the juncture box 45 in the elevator shaft, which juncture box leads to the controller for the main motor that controls the up and 20 down movement of the car.

In some instances an elevator shaft may have a door opening which is not as high as the rest of the openings, so that the gate or door does not travel as high as the average, and in this case the upper cut-out switch E will not come into service, and for this purpose a stationary cut-out switch F is arranged in the elevator shaft, as illustrated in Figs. 3 and 8. This switch is 30 suitably connected with the motor circuit and performs the same function as the switch E to cut out the motor and stop the gate as it rises. The gate 25^a, Fig. 8, represents the gate for the low door opening 26^a, and on this gate is a cam 25^b which strikes the arm f. of the switch F to thereby open the circuit of the motor and stop the same when the cam reaches the switch, which occurs at a time when the gate has reached 40 its full open position.

It is important that the member 14 of the pick-up device B be prevented from being projected at all times except when directly opposite a gate or landing, and consequently 45 a safety switch G is mounted on the car, and on the guide rail H in the elevator shaft are cams h opposite each landing, so that when the switch G reaches a cam h the plunger g of the switch is pressed inwardly so that 50 the bridging contact g² engages the fixed contacts g³ and places the motor circuit in condition for control by the pushbutton switches 37, 38, 39. As soon as the car moves from the landing the switch G will automatically open until it is again closed when 55 the car reaches another landing.

From the foregoing description taken in connection with the accompanying drawings, the advantages of the construction and 60 method of operation will be readily understood by those skilled in the art to which the invention appertains, and while I have described the principle of operation, together with the apparatus which I now consider to be the best embodiment thereof, I 65

desire to have it understood that the apparatus shown is merely illustrative and that such changes may be made when desired as fall within the scope of the appended claims.

Having thus described my invention, I claim as new and desire to secure by Letters Patent:

1. The combination of an elevator shaft, a car movable in the shaft, a sliding landing gate, a guide on the car parallel with the movement of the gate, a device movable along the guide, a member associated with the device, links movably connecting the member with the device, means with which the member is adapted to engage whereby the member moves into and out of engagement with the gate automatically by the movement of the device, and operator-controlled means on the car for actuating the device.

2. The combination of an elevator car, stationary vertical guideways thereon, weights movable in the guideways, gate-engaging elements, links connecting the elements with the weights, means cooperating with the elements for moving the same laterally into gate-engaging position at the beginning of the upward movement of the weights and retracting the elements at the end of the downward movement of the weights, and means on the car for operating the weights.

3. The combination of an elevator car, stationary vertical guides thereon, weights movable in the guides, gate-engaging elements, links connecting the elements with the weights, means cooperating with the elements for moving the same laterally into gate-engaging position at the beginning of the upward movement of the weights and retracting the elements at the end of the downward movement of the weights, and means on the car for operating the weights, said elements having a series of teeth, with a gate 105 mounted along the path of movement of the car and having projecting means with which the teeth of the elements engage to lift the gate with the said weights.

4. In an elevator, the combination of a car, vertically disposed guides thereon, weights movable in the guides, cables connected with the weights, a motor-driven winding means on the car for the cables, vertically disposed gate-engaging elements, 120 links connecting each element with an adjacent weight, means cooperating with the elements for causing the latter to be projected to gate-engaging position at the beginning of the lifting movement of the weights and to be retracted at the end of the return movement of the weights.

5. The combination of a car, a landing gate having a projecting element, a movable device on the car, a member linked to the

device, a stationary pin on the car, a hook on the member to normally engage under the pin, whereby the first part of the movement of the device upwardly causes the member to move into engagement with the projecting means on the gate, and means on the car with which the member engages during the last part of the return movement of the device, whereby the member is retracted 10 from the gate.

6. The combination of an elevator car, a landing gate, a guide on the car, a vertically movable device in the guide, a member having a lateral movement to engage and disengage the gate, parallel links connecting the member with the device, a hook on the member, an element with which the hook engages and disengages by lateral movement of the member, and means with which the member 15 engages during the last part of the movement of the device to hold the member against movement with the device, whereby

the member is retracted from engagement with the gate.

7. The combination of an elevator shaft, 25 closing elements for the landings of the shaft, some having a shorter travel than the others, with a car, electrically operated means on the car for automatically engaging an element to move the same open and closed, 30 manually operated switches on the car for controlling the running of the said electrically operated means, automatic switches on the car for stopping the electrically-operated means when a closing element having the 35 longer travel reaches the end of its movement in either direction, a switch at each landing at a door having the shorter travel, and means on such door of shorter travel for operating the last-mentioned switch to 40 stop the electrically operated means when the said door reaches its fully-open position.

JOHN E. W. FOGAL.
